ADHESIVE APPLYING MECHANISM FOR USE IN CARPET MAKING MACHINES

Harold P. Faris, Philadelphia, Pa., and John E. White, Trenton, N. J., assignors to National Automotive Fibres, Inc., Detroit, Mich., a corporation of Delaware

Original application October 28, 1940, Serial No. 363,196. Divided and this application April 24, 1943, Serial No. 484,432

8 Claims. (Cl. 91—30)

1

This invention relates generally to carpet making machines for manufacturing carpet of the type disclosed in United States Patent No. 2,187,140 dated January 16, 1940, and constitutes a division of our application filed October 28, 1940, bearing Serial No. 363,196.

One of the essential objects of the invention is to provide an improved mechanism for applying to the upper surface of suitable carpet material, such as a burlap covered base of rubber, a coating or layer of cement or other adhesive substance in which cut fibers, such as cut hair or the like, may be imbedded to form a pile simulating the pile of a conventional woven carpet.

Another object is to provide a mechanism of the type mentioned wherein a trough for the adhesive substance is provided at the discharge opening thereof with adjustable closure means for regulating the amount of adhesive substance discharged from said opening onto the carpet material. Preferably the amount of adhesive substance discharged from the trough is determined in accordance with the rate of advance of the carpet material and the thickness of the adhesive layer desired thereon.

Another object is to provide an adhesive applying mechanism having adjustable means for determining the width to which the adhesive substance may be applied to the carpet material.

Another object is to provide an adhesive applying mechanism which is capable of being adjusted along the path of the carpet material to position the doctor blade of such mechanism at the point where the advancing carpet material has little or no vibration, so that the doctor blade will produce a substantially uniform and even layer of adhesive substance on the carpet material.

Another object is to provide an adhesive applying mechanism wherein the doctor blade is adjustable vertically relative to the advancing carpet material so as to vary the thickness of the layer of adhesive produced thereby.

Another object is to provide an adhesive applying mechanism that is simple in construction, economical to manufacture, easy to install and efficient in operation.

Other objects, advantages and novel details of construction of this invention will be made more apparent as this description proceeds, especially when considered in connection with the accompanying drawings, wherein:

Figure 1 is a side elevation of a machine including an adhesive applying mechanism embodying our invention;

2

Figure 2 is a vertical longitudinal sectional view through the adhesive applying mechanism;

Figure 3 is a fragmentary top plan view of the structure shown in Figure 2;

Figure 4 is a fragmentary end view of the structure illustrated in Figure 2;

Figure 5 is a detail view of the wiper blade and associated parts;

Figure 6 is an end view of the structure illustrated in Figure 4;

Figure 7 is a diagrammatic vertical longitudinal sectional view through a part of our adhesive applying mechanism;

Figure 8 is a fragmentary elevational view of the hopper and actuating means for the closure for the discharge opening thereof;

Figure 9 is a vertical sectional view taken substantially on the line 9—9 of Figure 8.

Referring now to the drawings, A is an adhesive applying mechanism embodying our invention and constituting a part of a machine illustrated generally in Figure 1 for manufacturing carpet of the cemented pile type.

As shown in Figure 1 the carpet material 10, such as burlap covered rubber, is advanced through the machine with the burlap side thereof uppermost so that the upper surface of the burlap may be coated or covered with an adhesive substance or cement as the carpet material passes through the adhesive applying mechanism A. Cooperating belts 11 and 12 respectively are employed for withdrawing the carpet material from a roll 13, and other conveyor means including a belt 14 is employed for advancing the carpet material through the adhesive applying mechanism A and over suitable rotary beaters 15 which vibrate the carpet material after the adhesive substance is applied to the upper surface thereof. Cut fibers such as cut hair or the like are distributed from suitable means (not shown) onto the adhesive coating as the carpet material is vibrated by the beaters so that such fibers will be imbedded in the adhesive coating to form the cemented pile carpet.

Preferably the adhesive applying mechanism A has a trough 20 adapted to receive an adhesive substance or cement from a tank 21 and having a discharge opening 22 through which such adhesive substance may flow onto the upper surface of the advancing carpet material 10, and a doctor blade 24 engageable with the deposited adhesive substance 25 and adapted to determine the spread of the adhesive substance upon the upper surface of the carpet material 10 for subsequent engagement by the cut fibers aforesaid.

Cooperating with the doctor blade 24 is a roll 26 which is preferably made of steel and is of true cylindrical form to cooperate with the doctor blade 24 in governing the thickness of adhesive substance spread on the carpet material 10 as it advances beneath the doctor blade 24. Normally the doctor blade 24 is held in fixed relation to this roll 26 so that the spread of the adhesive substance 25 will be uniform, however, the doctor blade 24 may readily be adjusted vertically relative to the roll 26 to vary the thickness of the spread of adhesive substance on the carpet material.

Preferably the amount of adhesive substance discharged from the opening 22 in the trough 20 onto the carpet material 10 is determined in accordance with the rate of advance of the carpet material and the thickness of the spread desired. Such discharge opening 22 is in one side 28 of the trough 20 at the bottom thereof and is controlled by an adjustable closure element 29 which is preferably hingedly mounted at 30 upon the outer side of the trough 20.

For adjusting the closure element 29 we have provided an adjusting screw 31 threadedly engaging a bracket 32 on the outer side of the trough 20 and having at its outer end a knurled head 33 by which it may be manipulated, a sleeve 34 threadedly engaging the screw 31, a rod 35 mounted to turn in brackets 36 on the trough, a lever 37 fixed to the rod 35, a link 38 terminally connected to the lever 37 and sleeve 34, bifurcated levers 39 fixed to the rod 35, bifurcated levers 40 fixed to the closure element 29, links 41 and 42 respectively pivotally connected to the bifurcated levers 39 and 40, threaded rods 43 extending loosely through brackets 44 on the trough and terminally connected to the links 41 and 42, and coil springs 45 on the rods 43 between the links 42 and brackets 44. Thus, rotation of the adjusting screw 31 will cause the sleeve 34 to be adjusted lengthwise of said screw 31 and thereby cause the rod 35 to be turned by the intermediate link 38 and lever 37. Such turning movement of the rod 35 will cause the bifurcated levers 39 to move the links 41, rods 43, links 42 and levers 40 to thereby swing the closure element 29 about its pivot 30 relative to the discharge opening 22 of the trough for regulating the amount of adhesive substance to be discharged from said opening 22 onto the carpet material 10. The coil springs 45 tend to move the links 42 and levers 40 downwardly and to move the closure element 29 toward closed position. However, by suitably adjusting the screw 31 the closure element 29 may be moved to any suitable position relative to the discharge opening 22 in the trough to regulate the amount of adhesive substance discharged therefrom.

In Figures 7 and 9 respectively we have indicated by dotted lines one open position of the closure element 29, however such closure element may be adjusted to various other positions, as desired. Thus, with this construction it is possible to provide for a flow of adhesive substance from the trough 20 onto the carpet material 10 which may be continued without operator manipulation for an extended period.

In the present instance the roll 26, doctor blade 24, trough 20 and associated parts are mounted upon a carriage 50 that is adjustable along the path of the carpet material 10 so that the doctor blade 24 and roll 26 may be positioned at a point where the advancing carpet material 10 has little or no vibration to produce a substantially uni-

form and even layer of adhesive substance on the carpet material. In this connection it will be appreciated that the carpet material 10 is tensioned or under tension as it is advanced, hence it will have a natural tendency to vibrate at some points. Accordingly, when the carpet material 10 is under certain conditions of tension the doctor blade 24 might be gauging the spread of adhesive substance at a point of maximum tension in and vibration of the carpet material and therefore might cause the adhesive substance to be spread unevenly. To avoid this during operation of the machine, the tension of the carpet material 10 is adjusted to the desired amount and then the carriage 50 is adjusted back and forth along the path of the carpet material until the point of least vibration in the carpet material is found. The carriage 50 is then held in place so that the cooperating doctor blade 24 and roll 26 will function with uniformity of spread in mind. To accomplish this the carriage 50 is adjustable along a frame member 51 of the machine and has journaled thereon a shaft 52 carrying pinions 53 meshing with racks 54 fixed to the frame of the machine. Any suitable means such as a crank 55 may be employed at one end of the shaft 52 to rotate the pinions 53 relative to the racks 54 to cause the carriage 50 to move back and forth as aforesaid.

Before reaching the doctor blade 24 the upper surface of the carpet material 10 is engaged by the tip 60 of a suitable wiper blade 61 mounted upon the carriage 50. A supporting plate 62 for the advancing carpet material 10 is located beneath the wiper blade 61 and is carried by an adjustable bracket 63 on the carriage 50 so that such plate 62 may be adjusted relative to the wiper blade 61.

Mounted upon and adjustable transversely over the wiper blade 61 are blocks 64 carrying brackets 65 to which side plates 66 are connected at 67 for both longitudinal and vertical adjustment. Preferably these side plates 66 are below the trough 20 and substantially abut and conform in shape to the adjacent surface of the doctor blade 24. Such side plates 66 may be formed of any suitable material such as Bakelite and are adapted to determine the width to which the adhesive substance discharged from the trough 20 may be applied to the carpet material 10.

In use, the carpet material 10 with the burlap side thereof uppermost advances over the plate 62 and is wiped by the tip 60 of the blade 61 before the adhesive substance is deposited upon said material from the trough 20. The amount of adhesive substance discharged from the trough 20 onto the carpet material 10 is controlled by the closure element 29 and associated parts, and the width of application is determined by the side plates 66. The doctor blade 24 determines the spread and thickness of the adhesive substance on the upper side of the carpet material 10 as the latter advances by it. Thus, the desired adhesive coating or layer on the carpet material 10 is obtained before the carpet material reaches the rotary beaters 15 which vibrate said material as the cut fibers (not shown) are distributed onto the adhesive coating to be imbedded endwise therein in the usual manner to form the cemented pile carpet.

What we claim as our invention is:

1. Mechanism for applying an adhesive substance to the upper surface of advancing sheet material, comprising a roll for supporting the advancing material, means for discharging ad-

hesive substance onto the advancing material before it reaches said roll, a doctor blade engageable with the adhesive substance on said material when it reaches said roll to determine the spread of said substance on said material, and a carriage for said roll and blade supported for movement along the path of the advancing material to position said roll and blade at a point where the advancing material has little or no vibration, so that the doctor blade will produce a substantially uniform and even layer or coating of adhesive substance on said material as it passes over said roll.

2. Mechanism for applying an adhesive substance to the upper surface of advancing sheet material, comprising a doctor blade engageable with adhesive substance on said material to determine the spread thereof, means for discharging adhesive substance onto said material before it reaches the doctor blade, said means including a trough supported a sufficient distance above the sheet to discharge the adhesive substance in unrestricted flow through the atmosphere to the sheet material, means for wiping the material before the adhesive substance is deposited thereon, and means carried by one of the means aforesaid for determining the width to which the discharged adhesive substance may be applied to said material.

3. Mechanism for applying an adhesive substance to the upper surface of advancing sheet material, comprising a doctor blade engageable with adhesive substance on said material to determine the spread thereof, means for discharging adhesive substance onto said material before it reaches the doctor blade, said means including a trough supported a sufficient distance above the sheet to discharge the adhesive substance in unrestricted flow through the atmosphere to the sheet material, means for wiping the material before the adhesive substance is deposited thereon, and side plates carried by the wiping means below the discharging means for determining the width to which the discharged adhesive substance may be applied to said material.

4. Mechanism for applying an adhesive substance to the upper surface of advancing sheet material, comprising a doctor blade engageable with adhesive substance on said material to determine the spread thereof, means for discharging adhesive substance onto said material before it reaches the doctor blade, said means including a trough supported a sufficient distance above the sheet to discharge the adhesive substance in unrestricted flow through the atmosphere to the sheet material, means for wiping the material before the adhesive substance is deposited thereon, and means between the wiping means and doctor blade for determining the width to which the discharged adhesive substance may be applied to said material.

5. Mechanism for applying an adhesive substance to the upper surface of advancing sheet material, comprising means for discharging an adhesive substance onto said material, a wiper blade engageable with said material before the adhesive substance is discharged onto the same, a doctor blade engageable with the adhesive substance after it is on the material, brackets mounted upon and adjustable transversely over the wiper blade, said brackets extending toward said doctor blade, and side plates between the wiper blade and doctor blade mounted for both longitudinal and vertical adjustment on said brackets,

said side plates cooperating with the doctor blade to determine the spread of adhesive substance on said material.

5 6. Mechanism for applying an adhesive substance to the upper surface of advancing sheet material, comprising a trough above said material and having a discharge opening at the bottom thereof through which an adhesive substance may be discharged downwardly onto said surface, a doctor blade above said material and engageable with the discharged adhesive substance to determine the spread thereof upon said surface, a roll of true cylindrical form beneath said material and cooperating with said doctor blade to govern the thickness of the adhesive substance spread on said surface, and a carriage carrying the trough, doctor blade and roll and adjustable back and forth along the path of said advancing material whereby said doctor blade and roll may be positioned at a point where the advancing material has little or no vibration so that the doctor blade will produce a substantially uniform layer of adhesive substance on said material as it passes over said roll.

20 7. Mechanism for applying an adhesive substance to the upper surface of advancing sheet material, comprising a trough above said material and having a discharge opening at the bottom thereof through which an adhesive substance may be discharged downwardly onto said surface, a doctor blade above said material and engageable with the discharged adhesive substance to determine the spread thereof upon said surface, a roll of true cylindrical form beneath said material and cooperating with said doctor blade to govern the thickness of the adhesive substance spread on said surface, a carriage carrying the doctor blade and roll and adjustable back and forth along the path of said advancing material whereby said doctor blade and roll may be positioned at a point where the advancing material has little or no vibration so that the doctor blade will produce a substantially uniform layer of adhesive substance on said material as it passes over said roll, a wiper blade mounted on said carriage and engageable with said surface in advance of said doctor blade, and a supporting plate for said advancing material located beneath said material and adjustably connected to said carriage so as to be adjustable relative to said wiper blade.

35 8. Mechanism for applying an adhesive substance to the upper surface of advancing sheet material, comprising means for discharging an adhesive substance onto said material, said means including a trough above said material and having a discharge opening at the bottom thereof through which an adhesive substance may be discharged downwardly onto said surface, a doctor blade engageable with the discharged adhesive substance to determine the spread thereof upon said surface, a roll for supporting the advancing material beneath the doctor blade, said roll being of true cylindrical form to cooperate with the doctor blade to govern the thickness of the adhesive substance spread on said material, and a common carrier for said roll and doctor blade supported for movement back and forth along the path of the advancing material to position said roll and blade at a point where the advancing material has little or no vibration, so that the doctor blade will produce a substantially uniform layer of adhesive substance on said material.
